UNITED STATES PATENT OFFICE.

LYMAN R. ROBERTS, OF RUTHERFORD, NEW JERSEY, ASSIGNOR TO UNDERWOOD TYPE-WRITER COMPANY, OF NEW YORK, N. Y., A CORPORATION OF DELAWARE.

AUTOMATIC TYPE-WRITER OPERATOR.

1,181,958.

Specification of Letters Patent.

Patented May 2, 1916.

Original application filed August 31, 1911. Serial No. 646,975. Divided and this application filed November 20, 1912. Serial No. 732,400.

To all whom it may concern:

Be it known that I, LYMAN R. ROBERTS, a citizen of the United States, residing in Rutherford, in the county of Bergen and 5 State of New Jersey, have invented certain new and useful Improvements in Automatic Type-Writer Operators, of which the following is a specification.

This invention relates to an improvement 10 in platen actuating mechanism, and is a division of my application No. 646,975, filed August 31, 1911.

In my above-mentioned application, I showed certain mechanism of use in connection with an automatic operator for typewriters, and more especially means for feeding work members, such as envelopes to the platen. To properly position work members on the platen, as each one is supplied 20 thereto, it has been found desirable to give the platen several line-space movements in order to bring the desired point on the work member to the printing point of the typewriter. To do this, a special platen rotating mechanism is provided in addition to 25 the normal line-space mechanism. This platen rotating mechanism is controlled at a tracker or tracker-board by a perforated master member. The platen rotating mechanism is shown in this case in the form 30 of a ratchet wheel secured on the platen axle and driven by a pawl to rotate the platen. The pawl is mounted on a lever provided with a roller, which, when 35 the carriage is in its starting position at the beginning of a line, underlies an arm which may be swung by a pneumatic actuator when a certain perforation in the master sheet comes into register with corresponding 40 aperture in the tracker-board. The extent of movement of the pawl, and thus the extent of rotation of the platen, may be adjustably limited by a locking detent which is forced into engagement with another 45 ratchet wheel on the platen axle.

The broad purpose of the invention may be considered to include, among other things, the idea of using a plurality of different line-space mechanisms for the platen, 50 which line-space mechanisms may be controlled from different points, and arranged so that the different points of control may be brought selectively into action.

Other features and advantages will here- 55 inafter appear.

In the accompanying drawings, Figure 1 is a fragmentary sectional view, showing such of the parts as are necessary to illustrate the present invention in connection with a typewriter. Fig. 2 is a fragmentary perspective view, showing certain details of the special platen rotating mechanism. Fig. 3 is an enlarged detail section of one of the pneumatic controls, showing the relation of the primary and secondary pneumatics 60 thereof. Fig. 4 is a fragmentary top plan view. Fig. 5 is an enlarged detail top plan view of the special platen rotating mechanism. Fig. 6 is a view in elevation of the parts shown at Fig. 5. Fig. 7 is a skeleton detail view, showing the means whereby the active control is shifted from one master sheet to the other. Fig. 8 is a detail view, showing the means for actuating the normal line-space mechanism. Fig. 9 is a reduced 75 fragmentary perspective view of the two master sheets. Fig. 10 is a detail view in side elevation showing the normal line-space mechanism for the platen.

Referring more particularly to the separate parts of this invention, as embodied in the form shown in the drawings, 1 indicates a dotted outline of a typewriter, which is to be actuated by a typewriter operator indicated in general at 2^a. 80

In illustrating this invention, the typewriter 1 is shown to be of the usual Underwood type, and is provided with a carriage 2 mounted to run on ways on the frame of the typewriter, and having a platen 3 rotatably mounted in the usual manner. To be specific, the platen 3 is provided with an axle or shaft 4, which is journaled in the carriage 2 of the machine 1 and extends to one side at 5 where it is provided with the usual line-space wheel 150, which is operated through the intermediary of a slide and pawl 151 by the usual line-space lever 6 forming a normal line-space mechanism adapted to give a rotation to the platen 3 of 100 one or more line-spaces according to the particular adjustment of this line-space mechanism. This particular line-space mechanism may be of any suitable type, and in this instance indicates that generally in 105 use on Underwood typewriters. In this case, inasmuch as the typewriter is not to be operated by hand, but by a mechanical operator, means must be provided for actuating the line-space lever 6 to produce a nor- 110

mal line-space operation between the writing of two lines. For this purpose there is provided a connector 7 having an arm 8 with a slot 9 therein to engage over an upward standing finger 10 on the line-space lever 6. This connector 7 is arranged to be brought into engagement with a continuously driven member 11, shown in the form of a screw 11 rotating in fixed bearings.

10 The connector 7 is provided with a half nut 12 which, when the connector 7 is properly swung, comes into engagement with the threads of the screw 11, so that the connector will travel along the screw and thus 15 will actuate the line-space lever 6 to rotate the platen 3 one or more line-spaces according to the adjustment of the line-space mechanism. Of course, if the engagement of the connector 7 with the screw 11 is continued, not only will a line-space action take 20 place, but the carriage 2 will be returned toward its starting position for the beginning of a line.

The connector 7 is pivotally mounted on a 25 rod 13, so as to swing about this rod as a pivot and yet travel along the same. The connector 7 is also mounted so as to slide along a rod 14 and still be connected to this rod so that when the rod is moved bodily, 30 the connector 7 will be swung about the rod 13 as a pivot. The rod 14 is supported on a pair of arms 15 and 16, so that it can be swung back and forth. The rod 14 and the arms supporting the same are normally held 35 by the weight of the parts in a position corresponding to a position of the connector 7, such that the half nut thereon will be out of engagement with the screw 11.

In order to bring the connector 7 in operative engagement with the screw 11, there is 40 provided a plunger 18 slidingly supported on a rod 19, so that the end thereof is held adjacent to the rod 14. The plunger 18 is pivotally connected to a bell crank 20, so as 45 to be actuated by the latter. This bell crank 20 is in turn actuated through the intermediary of a link 21, by a pneumatic actuator 22. The pneumatic actuator 22 is shown to comprise a motor 23 and a pneumatic control 24, which in turn comprises a primary pneumatic 25 and a secondary pneumatic 26. The primary pneumatic 25 is connected by a pipe 27 and branch pipes 28 and 29 to a pair of trackers or tracker-boards 30 and 31. 55 The trackers 30 and 31 are normally covered by blank portions of a pair of master sheets 32 and 33 respectively, which, however, are provided with suitable apertures arranged to come into register with corresponding apertures in the trackers 30 and 31 when the master sheets are drawn across the face of the trackers.

When a perforation in a master sheet comes in register with an aperture on a 60 tracker, corresponding to the pneumatic ac-

tuator 22, air will be admitted to the primary pneumatic so as to cause the bellows motor 23 of this pneumatic actuator to be collapsed, causing the plunger 18 to shoot forward and engage the rod 14, forcing it 70 to such a position that the connector 7 will be swung about its pivot rod 13 bringing the half nut thereon into engagement with the screw 11.

The details of the pneumatic control 75 which enables this action will be seen by reference to Fig. 3. The air admitted at the tracker comes into the primary pneumatic through the pipe 27, so that this air comes into a chamber 34 always connected 80 to a suction chamber 35 by a bleed hole 36 in a diaphragm 37. The vacuum or suction chamber 35 is normally kept under a sub-atmospheric pressure by a vacuum pump 38 (see Fig. 1), which is connected thereto by 85 a pipe 39 and is driven by any suitable form of a motor indicated at 40. The air admitted through the pipe 27 when the latter is opened by a perforation in the master sheet, comes into the chamber 34 at a greater rate 90 than it can pass out through the small bleed opening 36, producing an unbalanced pressure on the diaphragm 37 so that the diaphragm is raised carrying with it a valve stem 41 resting thereon. The valve stem 95 41 carries a valve 42 which, when the diaphragm 37 is raised, will close an opening 43 in a partition 44 located between the vacuum or suction chamber 35 and chamber 45. The valve stem 41 also carries another valve 46, which uncovers an opening 47 permitting the outside air to come into the chamber 45. The chamber 45 is connected by a pipe 48 to a chamber 49 in the secondary pneumatic. This chamber 49 105 is separated from the chamber 35 by a diaphragm 51 and is normally under a sub-atmospheric pressure by being connected with the suction chamber 35 through the intermediary of the pipe 48, the chamber 45 110 and the port 43. The diaphragm 51 will be raised by the air rushing in the chamber 49, so that it carries up with it a valve rod 52 supporting a valve 53. The valve 53 normally closes an opening 54 in a partition 55, which separates the suction chamber 35 from a chamber 56. The chamber 56 is connected by a pipe 57 to the interior of the pneumatic motor 23, so that as soon as the valve 53 is raised, this motor will 115 be exposed to suction from the chamber 35 and the pump 38, causing it to collapse, and thus actuate the plunger 18. The valve stem 52 also carries a valve 58, which momentarily uncovers an opening 59 allowing a communication between the chamber 56 and the outside air. This opening 59, is however, almost immediately covered and closed by another valve 60 carried by the valve rod 52. 120 125 130 135 140 145 150 155 160 165 170 175 180 185 190 195 200 205 210 215 220 Thus far it has been shown how the normal line-space mechanism can be controlled in its actuation from either tracker-board and by either master sheet. It now remains 5 to be shown how the platen can be rotated by a special line-space mechanism, which can be used independent of the normal line-space mechanism, as in positioning a new work member, such as an envelop after it 10 has been supplied to the platen, so as to bring the proper point thereon in apposition to the printing point of the typewriter for the beginning of the printing of an address thereon. To accomplish this end, the 15 platen axle 4 has secured thereon a feeding ratchet wheel 61. A lever 62 is loosely mounted on the axle 4 so as to bring a pawl 63, carried thereby, into engagement with the teeth of the ratchet wheel 61. This 20 pawl 63 is forced by a spring 64 into engagement with the ratchet wheel 61, so that it will rotate the latter in one direction and yet be free to slip by the teeth of the ratchet wheel when moved in the other direction. 25 The lever 62 is held in a normal raised position by a spring drum indicated diagrammatically at 65. The lever 62 is provided with a contact roller 66, which is so located that, when the carriage 2 is drawn to its 30 extreme position to the right, that is to a position corresponding to the beginning of a line, it will underlie a projection 67 on an arm 68, which is pivotally mounted at 69 so as to swing down into engagement with 35 the contact roller 66. When the arm 68 is swung down, it will carry with it the lever 62 and thus cause the pawl 63 to rotate the ratchet wheel 61 and therefore rotate the platen 3. In order to limit the 40 extent of this rotation so that the platen will not be thrown beyond a predetermined point, there is provided a locking detent lever 70 pivotally mounted at 71 and normally held in a raised position against a stop 72 by 45 a spring 73. The detent 70 is extended, however, to such a position that it will be engaged by the lever 62 during its downward movement, so that the detent 70 will also be swung downwardly, during the final 50 movement of the lever, bringing a tooth 74 on the detent into engagement with a locking ratchet wheel 75, also secured to the platen axle 4, but having its teeth faced in the opposite direction to the direction in 55 which the teeth of the feeding ratchet wheel 61 face. This will cause a positive locking of the platen preventing it from rotating beyond a certain predetermined extent with each actuation of the lever 62. The extent 60 to which the lever 62 may move before coming into engagement with the detent 70 may be varied by varying the position of a head 76 which is adjustably mounted on the detent 70, and so located that it will be the 65 part first engaged by the lever 62.

The movements of the arm 68 may be controlled from one of the master sheets, preferably the master sheet 32, which controls the feeding of an envelop to the platen 3. To accomplish this there is provided a pneumatic actuator 77, comprising the usual pneumatic motor 78, and a pneumatic control 79 having primary and secondary pneumatics 80 and 81 respectively. The pneumatic control 79 is similar in its action to the pneumatic control 24, and has its primary pneumatic 80 connected by a conduit or pipe 82 to the corresponding aperture in the tracker 30.

When a certain perforation in the master sheet 32 comes into register with the corresponding aperture in the tracker 30, the air will be admitted to the primary pneumatic 80, so as to enable the interior of the motor 78 to be connected to the exhaust point 83, so that it will be collapsed to draw down on the arm 68 through the intermediary of a link 83.

When the master sheet 32 is fed far enough to cover the aperture in the tracker 30, the motor 78 will be connected to the atmosphere and cut off from the suction pump 38 by the pneumatic control 79, so that it will be free to expand under the pull of a tension spring 84, which at the same time restores, through the intermediary of the link 83, the arm 68.

In the embodiment shown in my application above mentioned, of which this is a division, as already stated, the upper master sheet 32 was illustrated as controlling the supplying and placing of the successive envelops on the platen, and the lower master sheet 33 was shown as controlling the writing of the address on the envelop, and also the actuation of the normal line-space mechanism for line-spaces between the several typewritten lines of the address. The two master sheets, however, are not in action at the same time, but are alternately brought in play as each finishes its specific work. To accomplish this, the master sheet 32 is stretched across the face of the tracker 30 by means of a pair of rollers 85 and 86, one of which may be used to feed the master sheet past the tracker. This is done by providing on the roller 85 a gear 87 located so that a gear 88 can be brought in mesh therewith. This gear 88 is secured to a shaft 89 mounted on a rocker 90. Shaft 89 is also provided with a gear 91 meshing with a gear 92, which is secured to a shaft 93 forming also a pivot for the rocker 90. Similarly the master sheet 33 is carried by a pair of rollers 94 and 95, the former of which may be provided with a gear 96 located so that a gear 97 can be brought into mesh therewith. The gear 97 is secured to a shaft 98 mounted on a swinging rocker 99. The shaft 98 also carries a gear 100.

which meshes with a gear 101 secured to a shaft 102, the latter also forming a pivotal mounting for the rocker 99. The gears 92 and 101 are continuously driven by a means 5 not shown.

The rockers 90 and 99 are provided with upturned ends engaged by rollers 103 and 104 mounted on the opposite ends of a shifting lever 105, which is pivoted intermediate its ends as at 106. The shifting lever 105 is so arranged that when it is swung in one direction, it will swing the rockers 90 and 99 so as to bring the gear 88 out of mesh with the gear 87 and drop the gear 97 into mesh with the gear 96, as shown in Fig. 7, and so that when it is swung in the opposite direction, it will swing the rockers 90 and 99 so as to bring gear 88 into mesh with the gear 87 and force the gear 97 out of mesh with the gear 96. Inasmuch as the gears 88 and 97 are constantly driven, it will be seen by this arrangement that the master sheets 32 and 33 can be alternately fed, but that both of the master sheets cannot be fed at the same time.

In order to shift the lever 105 there is provided a pair of plungers 107 and 108, which are arranged in apposition respectively, to pins 109 and 110 secured to the shifting lever 105 at opposite sides of its pivot. The plungers 107 and 108 are operated respectively by pneumatic actuators 111 and 112. These pneumatic actuators include pneumatic motors 113 and 114 connected to bell cranks 115 and 116, which actuate the plungers 107 and 108. These pneumatic actuators also include pneumatic controls 117 and 118 having the usual primary and secondary pneumatics. The pneumatic control 117 is connected to the tracker 31 by a pipe 119, and the pneumatic control 118 is connected to tracker 30 by a pipe 120. It will be seen that this is a cross connection so that the tracker 30 and the master sheet 32 control the throwing into operation of the tracker 31 and the master sheet 33 and vice versa. By this arrangement the master sheets are alternately brought into action and the one controls the bringing into action of the other. It will thus be seen that there are provided two separate and distinct mechanisms for rotating the platen, one the normal line-space mechanism and the other a special platen spacing mechanism, which mechanisms may be individually controlled from separate points, so that one means of rotating the platen can be used when the other is silent.

Variations may be resorted to within the scope of the invention, and portions of the improvements may be used without others.

Having thus described my invention, I claim:

1. The combination, with typewriting

mechanism, including a platen; of two separate platen-rotating mechanisms, one for imparting a single line-space movement, and the other for imparting a multi-line-space movement; and master-sheet mechanism for controlling the actuation of said platen-rotating mechanisms. 65 70

2. The combination, with typewriting mechanism, including a platen; of two separate master-sheet mechanisms; actuating mechanism therefor; a platen-rotating mechanism controlled by one of said master-sheet mechanisms for imparting a multi-line-space movement to said platen; and a separate platen-rotating mechanism controllable by either master-sheet mechanism for imparting a single line-space movement to said platen. 75 80

3. The combination, with typewriting mechanism, including a platen; of two separate platen-rotating mechanisms, one for imparting a single line-space movement, and the other for imparting a multi-line-space movement; and two separate master-sheet mechanisms, one of which solely controls the actuation of one of said platen-rotating mechanisms, and either of which may control the actuation of the other platen-rotating mechanism. 90

4. The combination, with typewriting mechanism, including a platen; of two separate platen-rotating mechanisms, one for imparting a single line-space movement, and the other for imparting a multi-line-space movement; two separate master-sheet mechanisms, one of which solely controls the actuation of one of said platen-rotating mechanisms, and either of which may control the actuation of the other platen-rotating mechanism; and means for shifting the control from either master sheet mechanism to the other. 95 100 105

5. In a typewriting machine, the combination with a platen, of two separate line-spacing mechanisms therefor, a pneumatic actuator for each of said line-spacing mechanisms, a master sheet for controlling each actuator, means for feeding the master sheets, and means for silencing one master sheet when the other is being fed. 110

6. The combination, with a platen; of a 115 line-space device therefor comprising a line-space lever; an actuator for said lever arranged to strike thereagainst, but normally out of contact therewith; and master-sheet mechanism for controlling the operation of 120 said actuator.

7. The combination with a platen, of two different line-space mechanisms for said platen, an individual actuator for each of said line-space mechanisms, a master control set for each actuator, and means for shifting the control from one control set to another control set; said means including

driving connections for each control set, the shifting means adapted to bring only one driving connection into action at a time.

8. The combination with a platen, of a line-space mechanism for said platen including a line-space lever mounted to swing in a vertical plane, means for striking downwardly on said line-space lever to effect a line-space action of said mechanism, and an air motor for operating said striking means.

9. The combination with a platen, of two distinct and separate line-space mechanisms for said platen, an individual actuator for each of said line-space mechanisms, a master control set for each actuator, said control sets being alternately active, and means for shifting the control from one control set to another control set, the shifting means being adapted to bring one of the control sets into action at one time.

10. The combination, with a rotary platen; of a device at one end of said platen for imparting a single line-space movement thereto; a separate device at the other end of said platen for imparting a multi-line-space movement thereto; and master-sheet mechanism for controlling the actuation of said devices.

11. The combination, with a rotary platen; of a device at one end of said platen for imparting a single line-space movement thereto; a separate device at the other end of said platen for imparting a multi-line-space movement thereto; an actuator individual to each of said devices; and master-sheet mechanism for controlling the activity of said actuators.

12. The combination with a rotary platen and a line-space ratchet wheel connected to rotate therewith, of a line-space lever, a pawl carried thereby to engage said wheel and rotate the platen, a locking ratchet wheel having its teeth faced in the opposite direction from those of the first-named wheel, a locking lever provided with a detent to engage said locking wheel, and an adjustable stop carried by the locking lever in the path of the line-space lever.

13. The combination, with a rotary platen, and a line-space ratchet wheel connected to rotate therewith; of a line-space lever rotatable about the platen axis; a pawl on said lever to engage and rotate said ratchet wheel; an impact member arranged to strike against and thereby actuate said lever, but normally out of contact with the same; operating means for said impact member; a locking lever in the path of said line-space lever to be actuated thereby; and means to form a locking connection between the platen and locking lever when the latter is actuated by the line-space lever.

14. The combination, with a rotary platen and a line-space ratchet wheel connected to

rotate therewith; of a line-space lever rotatable about the platen axis and having a contact roller; a pawl on said lever to engage and rotate said ratchet wheel; an actuating member arranged to strike against said contact roller, to actuate said line-space lever, but normally out of contact with said contact roller; and operating means for said actuating member.

15. The combination, with a rotary platen, and a line-space ratchet wheel connected to rotate therewith; of a line-space lever; a pawl operated by said line-space lever to engage and rotate said ratchet wheel; an impact member arranged to strike against and thereby actuate said line-space lever, but normally out of contact with the same; operating means for said impact member; and a locking lever for said platen adapted to be struck, and thereby actuated, by said line-space lever.

16. The combination, with a rotary platen and a line-space ratchet wheel connected to rotate therewith; of a line-space lever; a pawl operated by said line-space lever to engage and rotate said ratchet wheel; an impact member arranged to strike against and thereby actuate said line-space lever, but normally out of contact with the same; operating means for said impact member; and a locking lever for said platen having a stop thereon arranged in the path of, and adapted to be struck by, said line-space lever during its movement, so as to enable said line-space lever to operate said locking lever, said stop being adjustable to vary the point in said movement at which the striking occurs.

17. The combination, with a typewriting mechanism, including a carriage and a platen mounted on said carriage; of automatic mechanism acting to concomitantly return the carriage and impart a single line-space movement to the platen; and separate automatic mechanism acting solely to impart a multi-line-space movement to said platen.

18. The combination, with a platen; of a line-spacing device for said platen comprising a line-space wheel connected to rotate therewith, and a lever for rotating said wheel; an intermittent, reciprocatory impact member arranged above said lever and adapted to strike against and thereby actuate the same; an actuator for said impact member; and master-sheet mechanism for controlling said actuator.

19. The combination, with a platen; of a line-spacing device for said platen comprising a line-space wheel connected to rotate therewith, and a lever for rotating said wheel; an intermittent, reciprocatory impact member arranged above said lever and adapted to strike against and thereby actuate the same; a pneumatic actuator; a link

- connection between said impact member and said actuator, for operating the former upon the collapse of the latter; and master-sheet mechanism for controlling said actuator.
- 5 20. The combination, with a platen; of a line-spacing device for said platen, comprising a line-space wheel connected to rotate therewith, and a lever for rotating said wheel; a pivotally-mounted, depressible member having a projection arranged to strike against and thereby actuate said lever; an actuator for said impact member arranged beneath, and connected with, the same; and master-sheet mechanism for controlling said actuator.
- 10 21. The combination, with a platen and its axle; of a pair of ratchet wheels connected to rotate with said platen and having oppositely-facing teeth; a rocking line-space 20 lever pivotally mounted on said axle; a pawl operated by said line-space lever to engage and rotate one of said ratchet wheels; and a locking lever having a detent to engage the other ratchet wheel, and also having a 25 portion projecting into the path of the line-
- space lever to be struck thereby, to enable said line-space lever to operate said locking lever during its movement.
22. The combination, with a platen and its axle; of a pair of ratchet wheels connected to rotate with said platen and having oppositely-facing teeth; a rocking line-space lever pivotally mounted on said axle; a pawl operated by said line-space lever to engage and rotate one of said ratchet 30 wheels; a locking lever having a detent to engage the other ratchet wheel; and a stop carried by said locking lever and projecting into the path of the line-space lever, to be struck by the latter during its movement, 35 so as to enable said line-space lever to operate said locking lever during its movement, said stop being adjustable to vary the point in said movement at which the striking occurs.
